[57] **CLAIM**

The ornamental design for a combined cap and material applicator, as shown and described.

DESCRIPTION

FIG. 1 is a perspective view of a combined cap and material tooling applicator showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof;

FIG. 7 is a rear elevational view thereof;

FIG. 8 is a perspective view of an alternate embodiment of FIG. 1;

FIG. 9 is a left side elevational view thereof;

FIG. 10 is a right side elevational view thereof;

FIG. 11 is a top plan view thereof;

FIG. 12 is a bottom plan view thereof;

FIG. 13 is a front elevational view thereof; and,

FIG. 14 is a rear elevational view thereof.

The broken line showing the environmental structure of the combined cap and material applicator is for illustrative purposes only and forms no part of the claimed design.
